UNITED STATES PATENT OFFICE.

CHARLES W. DAKE, OF CHICAGO, ILLINOIS, ASSIGNOR TO THE PYLE-NATIONAL COMPANY, OF CHICAGO, ILLINOIS, A CORPORATION OF NEW JERSEY.

HEADLIGHT AND NUMBER MARK.

1,402,054.

Specification of Letters Patent.

Patented Jan. 3, 1922.

Application filed July 21, 1919. Serial No. 312,260.

To all whom it may concern:

Be it known that I, CHARLES W. DAKE, a citizen of the United States, residing at Chicago, in the county of Cook and State of Illinois, have invented a certain new and useful Improvement in Headlights and Number Marks, of which the following is a specification.

My invention relates to headlights and particularly to electric headlights for locomotives. It has for one object the construction of a headlight in which there is a large field of illumination with a smaller concentrically located field of illumination of greater intensity. Another object is the combination with a locomotive headlight casing of a number mark which will be readily repaired, changed or removed. My invention is illustrated more or less diagrammatically in the accompanying drawings, wherein—

Fig. 1 is a front elevation;

Fig. 2 is a section on the line $z-z$ of Fig. 1;

Fig. 3 is a side elevation of my headlight showing the number mark elevated.

Like parts are indicated by like characters throughout.

A is a headlight casing extended rearwardly as at A¹ to provide for the mounting of the light. A² is an annulus fitted within the larger diameter of the casing and finished on its interior with porcelain to serve as a reflector.

B is a supporting ring adapted to carry the plain glass B¹ and to close the front of the headlight.

C is a silvered mirror positioned in the center of the headlight and secured therein by the ring C¹ which is screwed to the main headlight casing.

D is the light source, in this case an incandescent light. E is a number plate housing substantially rectangular in shape and pivotally supported on the headlight casing at E¹ by means of the hinge and pin E². E³ is a rearwardly projecting lug on the number plate housing in opposition to the lug E⁴ of the headlight casing. E⁵ is a screw adapted to secure the number plate housing in position.

F is a transparent number plate removably mounted within the number plate housing. G is an incandescent light positioned upon the rearward extension A¹ of the head-

light casing and within the number plate housing.

Each of the two reflectors may be made in any desired manner but I have suggested for the primary or central reflector glass, 60 properly coated on the outside, and for the second or forward reflector, a porcelain finish either applied to the casing or fashioned separately and put in position on the casing. The primary reflector is the reflector which gives the powerful beam of light and the secondary reflector is the one which gives the apparent diameter of light and aids in the nearby lighting effect. The number plate device may be entirely removed by driving out the pin E² and the number plate may be removed and another substituted with any convenient device for holding in the glass. In order to change or repair the number plate, the rear screw connection is loosened and the number plate housing is raised and tilted forward when the number plate may be changed or repaired or the incandescent lamp removed or repaired. 80

I claim—

1. A headlight reflector comprising a casing enclosing primary and secondary reflecting surfaces, and a source of light therefor, the primary reflecting surface comprising a reflector of silvered glass, the secondary reflecting surface comprising a zone of porcelain applied to the surface of the casing, the two reflectors together forming a substantially continuous outwardly flaring reflector. 90

2. As a new article of manufacture a headlight reflector comprising a casing and a light supported within, a primary reflecting member distinct from but supported within said casing to the rear of said light source, 95 a second reflecting member formed integrally with the casing in advance of said source of light, the two reflecting members forming a substantially continuous, substantially parabolic outwardly flaring reflector, 100 the primary reflector being composed of material adapted to reflect light more efficiently than the secondary reflector.

3. As a new article of manufacture a headlight reflector comprising a casing, primary and secondary reflecting members therein, and a light source therefor, the primary reflecting member being distinct from but supported within the casing, the secondary reflecting member comprising a porcelain coat- 110

ing applied to the interior of the casing, the two reflecting members forming a substantially continuous outwardly flaring reflector.

4. As a new article of manufacture a head light reflector comprising a casing, primary and secondary reflecting members which present a substantially continuous surface and form together a substantially continuous parabolic reflector, a single source of light 10 therefor, the primary reflector being composed of material adapted to reflect light more efficiently than the secondary reflector.

5. As a new article manufacture a head light reflector comprising a casing, primary and secondary reflecting elements therein, a single source of light therefor, said primary

reflecting element comprising a reflector of silvered glass, distinct from but supported within the head light casing, the secondary reflecting element comprising a zone of porcelain applied to the surface of the interior of the casing, the two reflecting elements forming together, a substantially continuous substantially parabolic reflecting surface.

In testimony whereof, I affix my signature in the presence of two witnesses this 17th day of July 1919.

CHARLES W. DAKE.
